UNITED STATES PATENT OFFICE.

ROBERT A. MCQUITTY, OF LONDON, ENGLAND, ASSIGNOR TO GEORGE NELSON DALE
& COMPANY, LIMITED, OF WARWICK, ENGLAND.

APPARATUS FOR MANUFACTURING THIN SHEETS OF GELATIN.

Application filed August 2, 1923. Serial No. 655,367.

To all whom it may concern:

Be it known that I, ROBERT ATKINSON MCQUITTY, a subject of the King of Great Britain and Ireland, residing at 24 Holborn, 5 London, England, have invented new and useful Improvements in Apparatus for Manufacturing Thin Sheets of Gelatin (on which application has been made for Letters Patent in Sweden No. 1,354, filed 3rd May, 10 1923), of which the following is a specification.

The present invention relates to improvements in apparatus for carrying out the method of manufacturing thin sheets of 15 gelatin, described in my Patent No. 1,407,075. In that specification, a method is described in which the gelatin is coated in a thin film on the surface of a flexible web, which is then wound up over the curved 20 surface of a wheel and dried under tension, when the gelatin is easily stripped off without the necessity for mechanical stripping means, and either rolled up or cut to sheets of the desired dimensions.

25 Broadly stated, the invention comprises coating apparatus in the form of a rotating roller dipping into the liquid gelatin, so that it maintains a pool of the liquid between itself and the web or flexible foundation, 30 and the web is coated without touching anything solid, whereby scratches and damage to the coating surface of the web or foundation are avoided. This coating apparatus is preferably employed with a web or flexible foundation in endless form, which 35 passes vertically up from the coating apparatus, over a horizontally arranged surface, and then in slack form back to the coating apparatus. Tension is maintained in the 40 vertical and horizontal positions of the web by the weight of a roller which is carried in guide slots in close proximity to the coating apparatus. Above the flat or curved horizontal run of web which is under tension, a roof and side walls are provided and 45 air blown in or extracted by a suitable fan, pump, or the like, so that the gelatin is quickly dried when it is taken off and rolled up or cut into sheets.

50 The invention is illustrated in the accompanying diagrammatic drawings, in which—

Figure 1 shows the general arrangement of the apparatus for carrying out the invention, and

Figure 2 shows a section through the 55 coating apparatus on an enlarged scale.

Referring now to the drawings, 10 is a gelatin tank, 11 the rotating roller and 12 the pool of gelatin maintained by the rotation of the roller, between itself and the 60 flexible foundation 1 passing over the power-driven rollers 2 and the curved surface 3. 5 the tension roller working in slots 6, and 7 the vertical run of the foundation. 8 is the roof and 9 the air pump 65 supplying hot air to the gelatin surface running over 3.

The ends of the web or flexible foundation are joined together with a stiffening 70 rod at each end, connected with a flexible binder, such as tape, cord, etc., so as to allow of continuous motion over a flat or curved surface, and then in slack and curved form back to the starting point. This journey is 75 repeated as often as necessary to complete the drying of the gelatin on the flexible band. On repeat journeys, the gelatin supply in the tank is cut off unless it is desired to add a second coat of gelatin.

The use of a rotating feed roller makes 80 it possible to coat the foundation with very liquid gelatin and to repeat the coating of gelatin thereon a sufficient number of times to obtain a coating of the desired thickness. The advantage obtained from 85 using gelatin in a very liquid form lies in the fact that the more gelatin is heated to evaporate the moisture contained therein in order to thicken its consistency, the more the colour and strength of the gelatin deteriorates, and consequently edible sheets manufactured from thin or very liquid gelatin 90 have a very much better appearance and are of a higher quality than those sheets manufactured from gelatin of a thicker consistency, the thicker consistency having been 95 obtained by the evaporation of the water contained in the gelatin at a fairly high temperature.

100 What I claim is:—

1. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank and adapted to rise vertically from said tank and then to pass

- horizontally over a supporting surface where the gelatin is dried under an air draught and from thence back to the tank for a repeat coating without the surface of the web or the said gelatin coating thereon touching anything solid and means adapted to maintain a supply of gelatin in contact with the web during its passage through the tank.
2. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank and adapted to rise vertically from said tank and then to pass horizontally over a supporting surface where the gelatin is dried under an air draught and from thence back to the tank for a repeat coating without the surface of the web or the said gelatin coating thereon touching anything solid, means for maintaining the web under tension in both the vertical and horizontal positions and means adapted to maintain a supply of gelatin in contact with the web during its passage through the tank.
3. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank and adapted to rise vertically from said tank and then to pass horizontally over a supporting surface where the gelatin is dried under an air draught and from thence back to the tank for a repeat coating without the surface of the web or the said gelatin coating thereon touching anything solid, a roller mounted in slot bearings for maintaining the web both in the vertical and horizontal positions and means adapted to maintain a supply of gelatin in contact with the web during its passage through the tank.
4. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank, and to rise vertically from said tank and then to pass horizontally over a supporting surface where the gelatin is dried under an air draught, and from thence back to the tank for a repeat coating without the surface of the web or said gelatin coating thereon touching anything solid, and a rotatable feed roller mounted in the tank adapted to raise a pool of liquid gelatin from the tank and to maintain this pool in contact with the web.
5. Apparatus for manufacturing thin sheets of gelatin in which liquid gelatin is coated on a web and the coat thus formed dried under tension and stripped therefrom when dry, comprising a tank, a moving web adapted to travel in close proximity to said tank, and to rise vertically from said tank and then to pass horizontally over a supporting surface where the gelatin is dried under an air draught, a roller mounted in vertical slot bearings adapted to maintain the said web in both the vertical and horizontal positions, and a rotatable feed roller mounted in the tank adapted to raise a pool of liquid gelatin from the tank and to maintain this pool in contact with the web so that the coating is done without the surface of the web or the gelatin coating thereon touching anything solid.
6. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank, and to rise vertically from said tank and then to pass horizontally over a supporting surface where the gelatin is dried under an air draught, a roller mounted in vertical slot bearings adapted to maintain said web in both the vertical and horizontal positions, and a rotatable feed roller mounted in the tank adapted to raise a pool of liquid gelatin from the tank and to maintain this pool in contact with the web so that the coating is done without the surface of the web or the gelatin coating thereon touching anything solid.
7. Apparatus for manufacturing thin sheets of gelatin in which liquid gelatin is coated on a web and the coat thus formed dried under tension and stripped therefrom when dry, comprising a tank, an endless moving web adapted to travel in close proximity to said tank and to rise vertically from said tank and then to pass horizontally over a supporting surface where the gelatin is dried on an air draught and from thence back to the tank for a repeat coating without the surface of the web of the said gelatin coating thereon touching anything solid, a roller mounted in slot bearings in proximity to said tank adapted to maintain said web in both the vertical and horizontal positions and a rotatable feed roller mounted in the tank adapted to raise a pool of liquid gelatin from the tank and to maintain this pool in contact with the web.

In testimony whereof I have signed my name to this specification.

R. A. McQUITTY.
